UNITED STATES PATENT OFFICE.

RUDOLPH J. LINDHORST, OF CLEVELAND, OHIO.

RUG FASTENER.

Application filed November 14, 1924. Serial No. 749,910.

This invention relates to rug fasteners of the type embodied in my Patent Number 1,509,047 granted September 16, 1924 and has for an object the provision of an invisible device which will effectively secure a rug in place, yet will permit ready removal when desired.

A further object is to provide a rug fastener the use of which will eliminate marks on highly polished floors and at the same time reliably secure a rug in place.

It is likewise an object to provide a rug fastener wherein a portion thereof is designed for semi-permanent attachment to the floor and other parts are detachably carried by the rug to be fastened to the floor.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Figure 1 is a top plan view of one of my fasteners, the outline of a rug being indicated in dotted lines;

Figure 2 is a substantially vertical central longitudinal section of the parts shown in Figure 1;

Figure 3 is a detail perspective view of the fastener, one corner being upturned to show the adhesive; and

Figure 4 is an enlarged sectional view showing the manner in which connection between the several parts is effected.

Having particular reference to the drawings throughout which like reference characters designate like parts this improved rug fastener may be stated as comprising a sheet 10 of fabric or the like having a coating 11 of adhesive material upon its lower face. At spaced points pairs of slits are formed in the sheet 10 to form aligned pockets 12 whose function will be hereinafter apparent. The above elements complete the portion which is attachable semi-permanently to the floor through adhesion of the coating 11 upon the main sheet 10 as shown in Figure 3 of the accompanying drawings. A sheet of crinoline 10' is arranged to protect the lower side of the sheet 10 as shown. A yieldable connecting bar 13 preferably formed of light spring metal is arranged for connection to a rug R, connection being

effected through employing a brad 14 whose legs 15 extend through a central opening 16 formed in the bar 13. These legs 15 are then bent in opposite directions and consequently 60 form a reliable connection between the rug and bar. It is understood that the brad head 17 may be of a color similar to that of the particular rug so as to render the fastener practically invisible.

The opposite ends 18 of this connecting bar 13 are tapered to sharp points whereby to assist in guiding the bar ends through the aforementioned pockets 12, it being obvious that arranging said ends in the pockets effects the removable connection between the rug R and sheet 10. The pointing of the ends also allows use of the connecting bar as a punch to form an opening in the rug through which the brad legs 15 are extended. 75 For the purpose of preventing relative shifting of the sheet 10 and the rug or connecting bar, I form the inner slits of the pockets of a length corresponding with the width of the connecting bar at its points of entry 80 into the pockets. As shown in Figure 4, each pocket 12 is lined with a fabric preferably crinoline to prevent adhesion of the sheet 10 to the ends of the connecting bar 13. The bar being tapered towards its ends 85 is not capable of either longitudinal or transverse movement in view of the structure just set out.

In using such a fastener the sheet 10 is first secured to the floor and the connecting 90 bar 13 is fastened to the rug. Then, as shown in Figure 4, the tapered ends of the connecting bar are sprung downwardly and guided into the pockets 12. The operation is now complete, and as is clear, separation 95 of the rug may be effected through simply lifting the portion immediately above the sheet 10, this lifting serving to bow upwardly the intermediate parts of the bar, resulting in withdrawal of the pointed ends from 100 the pockets 12.

Certain minor changes may be resorted to and such of these changes as may fall within the scope of the appended claims, I consider within the spirit of my invention.

I claim:

1. A rug fastener comprising a sheet having adhesive on one face to permit attachment to a floor, a resilient connecting bar having sharpened ends to engage the sheet, and means to separably connect said bar and a rug.

2. A rug fastener comprising a sheet having adhesive on one face to permit attachment to a floor, a resilient connecting bar having a central aperture, said bar having pointed ends to engage the sheet, and a brad arranged to separably connect said bar and a rug.

3. A rug fastener comprising a sheet having an adhesive material on one side to ef-

fect connection to a floor, pockets carried by the sheet, a resilient connecting bar having pointed ends receivable in the pockets, said bar having a central opening, and a brad arranged in the opening to secure the bar and a rug together.

15
In testimony whereof I affix my signature.

RUDOLPH J. LINDHORST.
